UNITED STATES PATENT OFFICE.

JOHN E. WHITTLESEY, OF CLEVELAND, OHIO.

AIRSHIP.

Application filed June 25, 1927. Serial No. 201,335.

This invention relates to improvements in airships and more particularly, to that type of airship embodying rigid gas containers, the general object of the invention being to 5 provide an extremely simple and inexpensive construction applicable alike to both large and small airships and of a nature which will afford maximum protection and safety without sacrificing speed.

10 In carrying out my invention, I propose an arrangement wherein a plurality of metal tubes or cylinders, say twenty, and preferably corrugated to increase their strength and rigidity, are longitudinally grouped in 15 abutting, interlocking relation, each of said tubes or cylinders being provided at suitable intervals with partitions or bulkheads forming separate or independent gas receiving chambers or compartments, the series or 20 group of tubes or cylinders being enclosed within a suitable metal casing of air-tight construction.

In the accompanying drawings, illustrating 25 my invention, Fig. 1 is a side elevation of my improved airship; Fig. 2 is a longitudinal sectional view thereof on the line 2—2, Fig. 3, the showing being somewhat conventional for clearness of illustration; Fig. 3 is an enlarged cross sectional view on 30 the lines 3—3, Figs. 1 and 2; and Fig. 4 is an enlarged detail sectional view on the line 4—4, Fig. 3.

The air ship illustrated in the drawings 35 comprises a plurality of rigid tubes or cylinders 1, twenty being here shown, which tubes or cylinders may be of any suitable size, depending upon the lifting capacity desired, and of any suitable material, aluminum or aluminum alloys being particularly satisfactory because of their light weight. Said 40 tubes or cylinders are longitudinally arranged or assembled in abutting relation, and are preferably corrugated not only to increase their strength and rigidity, but to 45 enable them to positively interlock one with the other, as clearly indicated in Figs. 3 and 4. In the present embodiment of the invention, each tube is provided with annular corrugations which provide an interlocking arrangement of tubes which effectively prevents longitudinal movement of 50 any one tube relative to the others.

These tubes or cylinders are of varying 55 length, the longest one being at the center of the group and the shortest ones being on

the outside thereof, with the result that a tube or cylinder structure is provided having substantially tapering front and rear end portions, affording the desired reduction to 60 air resistance.

Preferably, and as shown, this group of interlocking tubes or cylinders is enclosed within a suitable metal casing 3, of air-tight character, so that the spaces between the tubes or cylinders may be filled with gas, if 65 desired. Said casing is preferably provided with longitudinal corrugations to not only increase its strength and rigidity but to also enable it to conform to or interlock with the outside tubes or cylinders, as clearly indicated in Fig. 3.

Each of the tubes or cylinders is provided at suitable intervals throughout its length with partitions or bulkheads 5, forming a series of gas receiving chambers or compartments 7. Said chambers or compartments are separate or independent and not intercommunicating, so that the entire tube structure is not incapacitated should damage occur to one or to a limited number of said 75 chambers or compartments. Preferably, and as shown, the partitions or bulkheads of one tube are arranged in staggered relation to the partitions or bulkheads of the adjacent tubes, all partitions or bulkheads being preferably corrugated. An exceptionally strong and sturdy tube structure is therefore provided and which is, at the same time, relatively light in weight.

The two bottom tubes or cylinders 9 are 80 separated by a longitudinally disposed casing 11, which is arranged below the longitudinal axis of the tube structure, as clearly indicated in Fig. 3. Said casing may be made of any suitable material, such as aluminum or aluminum alloys, and of any suitable size, being here shown as having its upper corrugated portion 12 terminating at substantially the top of the two tubes or cylinders 9 and its lower portion 13 extending some distance below said tubes. A horizontally disposed partition 15 between said casing portions provides an upper, longitudinally extending chamber 16 and a lower, longitudinally extending chamber, the latter being divided by a horizontal partition 17 into upper and lower compartments 18 and 19 respectively. The upper chamber 16 and the upper compartment 18 may be used for the accommodation of passengers and the 100 105 110

crew, while the lower compartment 19 may be used to house the machinery of the ship, as will be readily understood. The usual driving motors and propellers 22 are mounted at the sides of the casing 11, and the side walls of said casing are provided with the usual windows 23. The ship is also provided with the usual rudders 25 at the rear. In order to provide access for the crew to the rooms 27 at the front and rear ends of the ship, pasageways 28 are provided which lead to said rooms from the upper chamber 16 of the casing 11.

From the foregoing, it will be seen that I have provided an airship construction which is of exceedingly simple and inexpensive form which may be used in the building of both large and small airships and withal, a construction which affords maximum safety, comfort and protection.

While one specific embodiment of the invention has been shown and described, it will be understood that many details of the construction may be varied or omitted without departing from the spirit and scope of the invention.

Having described my invention, I claim:

1. In an airship, a substantially cylindrical group of rigid, gas receiving, corrugated tubes arranged in longitudinal abutting, interlocking relation, and means for maintaining said tubes in such relation. 30

2. In an airship, a substantially cylindrical group of rigid, gas receiving tubes arranged in longitudinal abutting relation, each of said tubes being provided with annular corrugations so that said tubes are interlocked one with the other and longitudinal movement of any one tube relative to the others is prevented, and means for maintaining said tubes in such relation. 35

3. In an airship, a substantially cylindrical group of rigid, gas receiving, corrugated tubes arranged in longitudinal abutting interlocking relation, a casing enclosing said tubes and provided with longitudinal corrugations for interlocking engagement with the outer tubes of said group. 40 45

In testimony whereof I hereby affix my signature.

JOHN E. WHITTLESEY.
